UNITED STATES PATENT OFFICE.

CHARLES HENRY JOHNSON, OF PETALUMA, CALIFORNIA.

SEAL ATTACHMENT FOR LOCKS.

939,699.

Specification of Letters Patent.

Patented Nov. 9, 1909.

Application filed March 13, 1909. Serial No. 483,137.

To all whom it may concern:

Be it known that I, CHARLES H. JOHNSON, a citizen of the United States, and a resident of Petaluma, in the county of Sonoma and State of California, have invented a new and Improved Seal Attachment for Locks, of which the following is a full, clear, and exact description.

This invention relates to seal attachments 10 for locks, especially those locks used on suitcases, trunks, boxes for legal papers, jewel boxes and the like.

The object of this invention is to provide 15 a device whereby a seal may be placed over the lock and the same covered up and protected, so that the lock itself cannot be unlocked without breaking the seal.

The invention further consists of the construction and combination of parts to be 20 more fully described hereinafter and particularly pointed out in the claims.

Reference is to be had to the accompanying drawings forming a part of this specification, in which like reference characters 25 denote corresponding parts in all the views, and in which—

Figure 1 is a side view of the device, showing the seal attachment on the plate of a lock; Fig. 2 is an enlarged section on the 30 line 2—2 of Fig. 1; Fig. 3 is a view of the back of the plate of a lock, showing the means of fastening and locking the seal attachment to the lock-plate; Fig. 4 is an enlarged section on the line 4—4 of Fig. 1; 35 and Fig. 5 is an enlarged section on the line 5—5 of Fig. 3, showing the means of locking the seal attachment to the lock-plate.

Referring more particularly to the separate parts of the device, 1 indicates a lock of 40 any usual construction; 2 represents a cover-plate pivotally secured to the plate of the lock by a concealed hinge 3. This hinge 3 is of such a form and so located behind the plate of the lock that it cannot be picked 45 from the outside. The cover-plate 2 has a key-hole opening 5 therein, through which a key may be inserted into the key-hole opening 6 in the plate of the lock. The opening 5 in the cover 2 is adapted to be 50 closed by means of a protector 7. This protector is of any suitable form, but preferably is hinged to the cover 2 at one end by means of a pin 8, and is turned up at the other end slightly, as shown at 9 in Fig. 4. 55 This turned-up end 9 permits it to be easily caught hold of to revolve it about its pivot 8.

Just above the turned-up portion 9 on the protector 7, is an indentation 10 on its under surface. This indentation 10 is adapted to be engaged by the head of a pin 11 which 60 pierces the cover 2. This pin 11 is adapted to engage the indentation 10 on the protector to lock it over the key-hole opening. The head of another pin 12, passing through the cover-plate 2, is adapted to engage the same indentation on the protector 7 to hold it in a position away from the key-hole when it is desired to insert the key in the lock. The pins 8, 11 and 12 pass through the cover 2 and have sharpened points 13 which are 65 adapted to pierce through a seal 14 placed between the cover and the lock. These points 13 after passing through the seal 14 engage in recesses in the front of the lock-plate, as at 15. Thus, these pins serve the 70 double function of forming supports and locks for the protector 7 and for holding the seal in place. This seal 14 may be of any suitable material, such as wax or paper, and is adapted to be placed between the cover 75 and the lock proper so as to protect the latch or key-hole in said lock.

The cover 2 has a latch 16 (see Fig. 5), which passes through an opening in the seal and lock and is adapted to be engaged 80 by a locking-member 17 pivotally secured at 85 18 to the inner surface of the lock-plate. The locking-member 17 has a downwardly-extending portion 19 which engages the latch 16 and prevents it from being withdrawn. This locking-member 17 is also 90 slidingly held by a pin 20 fastened into the lock-plate, which engages a slot 21 in the locking-member. A spring 22, suitably secured to the lock-plate, engages the locking- 95 member 17 and holds it in such a position that it will automatically engage the latch 16.

At the top of the key-hole opening 6 in the lock-plate is a collar 23 which prevents the locking-member 17 from being lifted off 100 the latch 16 by the means of a wire.

In the operation of the device, the box or other receptacle is first locked, then the key removed and a seal of any suitable form placed over the opening. Then the cover 2 105 is closed and the pin-points 13 pierce the seal and hold it in place, and the cover is automatically locked in its closed position, as shown in full lines in Fig. 2. In order to open the lock, or even to get at the seal, the 110 lock itself must be first unlocked, and this can only be done by breaking through the

seal. The cover-plate 2 is made with a very slight bevel on its inner surface, to permit room for the seal and at the same time fit closely to the surface of the lock-plate.

5 Having thus described my invention, I claim as new and desire to secure by Letters Patent:

1. In a device of the class described, the combination with a lock, of a seal for said lock, a cover for said seal having an opening therein, a protector for said opening, means adapted to hold said protector over the opening, and a lock adapted to engage said protector when in its position away from the opening and also adapted to hold it in such position.

2. In a device of the class described, the combination with a lock, of a seal for said lock, a cover for said seal, having an opening therein, a protector for said opening, and a pivot-pin for said protector, adapted to hold the seal in place.

3. In a device of the class described, the combination with a lock, of a seal for said lock, a cover for said seal, having an opening therein, a protector for said opening, a pin adapted to support said protector and to pierce said seal, a pin adapted to hold said protector over the opening and to pierce said seal, and a pin adapted to hold said protector away from the opening and to pierce said seal.

4. In a device of the class described, the combination with a lock having a front plate, of a seal for said lock, and a cover for said seal having a concealed hinge located behind the front plate.

5. In a device of the class described, the combination with a lock having a front plate, of a seal for said lock, a cover for said seal having a concealed hinge located behind the front plate, and means for locking said cover to the lock.

6. In a device of the class described, the combination with a lock having a front plate, of a seal for said lock, a cover for said seal, a concealed hinge located behind the front plate adapted to connect said

cover to said lock, and means for locking said cover to said lock.

7. In a device of the class described, the combination with a lock having a key-hole therein, a seal for said lock, a cover for said seal, hinged to said lock, said cover having a key-hole therein corresponding to the key-hole in the lock, a protector for said key-hole, pivoted to said cover, means for locking said protector over the key-hole and a pin adapted to engage said protector and hold it away from the key-hole, a latch on said cover, a locking-member on said lock, adapted to engage said lock, and means for forcing said locking member into engagement with said latch.

8. In a device of the class described, the combination with a lock, of a seal for said lock, a cover for said seal having an opening therein, a protector for said opening, a pin on said cover adapted to support said protector and to pierce said seal, and a pin on said cover adapted to hold said protector over the opening and to pierce said seal.

9. In a device of the class described, the combination with a lock, of a seal for said lock, a cover for said seal having an opening therein, a protector for said opening, a pin on said cover adapted to support said protector, and a pin on said cover adapted to hold said protector away from the opening and to pierce said seal.

10. In a device of the class described, the combination with a lock, of a seal for said lock, a cover for said seal having an opening therein, a protector for said opening, a pin on said cover adapted to support said protector and to pierce said seal, and a pin on said cover adapted to hold said protector away from the opening and to pierce said seal.

In testimony whereof I have signed my name to this specification in the presence of two subscribing witnesses.

CHARLES HENRY JOHNSON.
